UNITED STATES PATENT OFFICE.

JOSEPH J. LAMPERT, OF SEATTLE, WASHINGTON.

GAS-SAVING DEVICE.

1,192,435.

Specification of Letters Patent. Patented July 25, 1916.

Application filed October 18, 1915. Serial No. 56,452.

To all whom it may concern:

Be it known that I, JOSEPH J. LAMPERT, a citizen of the United States, and a resident of Seattle, in the county of King and State of Washington, have invented certain new and useful improvements in Gas-Saving Devices, of which the following is a full, true, and exact specification.

My invention relates to gas saving devices and has for its principal object to provide a device which automatically breaks up, agitates and more thoroughly mixes a charge of gas and air for internal combustion engines.

15 A further object is to provide a valve for admitting the air to the device; still a further object is to provide a novel means of securing an agitation spring to its seat.

In combustion practice, it is a well known fact that the more finely divided and more thoroughly mixed a charge of air and gas can be delivered to the combustion chamber, the more complete will be the combustion; further a thinner mixture can be used if well mixed with a resulting saving in gas. The collection of carbon and dirt on all forms of screens is objectionable and renders them of little service. Carbon does not seriously affect my device.

30 Other objects will appear as my invention is more fully explained in the following specification, illustrated in the accompanying drawings and pointed out in the appended claims.

35 In the drawings, Figure 1 is a fragmentary view of a gas engine with my device shown in place. Fig. 2 is an enlarged plan of my device with parts broken away. Fig. 3 is a section on line x-x of Fig. 2.

40 Referring more particularly to the drawings, numeral 1 indicates a gas engine having a carbureter 2 and manifold 3, all of which are usual. My device is insertable between the manifold 3 and carbureter 2 and 45 consists of a flange 4 having holes 5 in either end of standard size and spacing to take the usual bolts used to secure the manifold and carbureter together. Flange 4 is centrally bored as at 6 and is counter-bored as at 7 to

50 receive the clench ring of a cone shaped spiral spring 8 of light spring material preferably piano wire. On one edge of flange 4 is an air inlet 9 at the outer end of which an air valve is secured. The air valve 55 consists of a cylinder 10 having an annular groove 11. A cap 12 fits over cylinder 10

and is held revolvably in place by a screw 13 which projects into groove 11. A cut 14 is made through both cap and cylinder for the admission of air. A lever 15 secured to the cap 12, allows the openings in the cap and cylinder to be put in or out of register as desired. A turnbuckle rod 16 connects the lever 15 to the throttle rod 17 so that the valve and throttle are both operated at the same time. A projection 18 on the clench ring of the spring 8 enters the passage 9 and further assists in holding the spring in place and in breaking up the air. As the gas passes up through the device, the air is sucked in and the mixture passes up through the spring cone which is in constant motion due to the vibration of the engine. This constant motion churns the gas and air into a thorough and minute mixture and also prevents dirt and carbon from accumulating on the spring.

While I have shown a particular form of embodiment of my invention, I am aware that many minor changes therein, will readily suggest themselves to others skilled in the art without departing from the spirit and scope of the invention, and I therefore desire to avoid being limited to the exact form shown and described, except as pointed out in the appended claims.

Having described my invention, what I claim as new and desire to protect by Letters Patent, is—

1. In a device of the character described, including an open flange adapted to be inserted between the carbureter and manifold of a gas engine and to be secured in place by the connecting means of the said manifold and carbureter, the combination of an annular groove around the opening in said flange, a light coiled spring cone terminating at its longer end in a clench ring adapted to removably fit into said groove and hold said cone in place, the vibration of said gas engine being sufficient to keep the said cone in constant motion, whereby air and gas from the carbureter are churned and thoroughly intermixed into a highly explosive mixture.

2. In a device of the class described including a flange having a circular opening therethrough, the combination of an annular groove around the inside of said opening, a fully vibrating coiled spring cone, a spring 100 clench ring formed integrally with the base of said cone and adapted to be removably

retained in said annular groove by means of the inherent spring in said clench ring.

3. In a device of the class described including a cylindrically cored flange having an air admitting valve on one side thereof and communicating with said core, the combination of an open groove around the inner periphery of said core and communicating with a passage leading to said air valve, a 10 freely vibrating coiled spring cone positioned in the cored portion of said flange and projecting above said flange, and means

removably retaining said core in said cone, said means including a clench ring integral with the base of said cone, and a projection 15 upon said clench rings, the said projection extending into said air passage and the clench ring fitting into said open groove, whereby the inherent spring of the clench ring will retain the said ring in the said 20 groove and the apex of the cone will be entirely free to vibrate.

JOSEPH J. LAMPERT.
